Primary Examiner — Bridget L Eland(74) *Attorney, Agent, or Firm* — Maier & Maier, PLLC(57) **CLAIM**

The ornamental design for a drill stop aid for surgical use, as shown and described.

DESCRIPTION

FIG. 1 is a front view of a drill stop aid for surgical use, showing our design;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a perspective view thereof; and,

FIG. 8 is an exploded perspective view thereof.

The broken line elements throughout the Figures illustrate portions of the drill stop aid for surgical use and form no part of the claimed design. The broken line bracket shown in the FIG. 8 view indicates the association of elements of the exploded view; the bracket forms no part of the claimed design.
